(57) **CLAIM**

The ornamental design for a shoe as shown and described.

DESCRIPTION

FIG. 1 is a perspective view of the shoe along a left side of the shoe;

FIG. 2 is a perspective view along a right side thereof;

FIG. 3 is a right side view thereof;

FIG. 4 is a left side view thereof;

FIG. 5 is a top plan view thereof;

FIG. 6 is a bottom plan view thereof;

FIG. 7 is a front view thereof; and,

FIG. 8 is a back view thereof.

The embodiment of FIGS. 1-8 shows a shoe to be worn on a left foot. The views for the embodiment of FIGS. 1-8 would be mirrored for a shoe to be worn on a right foot. Broken lines form no part of the claimed design.
